UNITED STATES PATENT OFFICE.

CHARLES EUGENE RISER, OF DAYTON, OHIO, ASSIGNOR TO THE CRAWFORD,
McGREGOR AND CANBY COMPANY, OF DAYTON, OHIO, A CORPORATION OF
OHIO.

CONTOURING-MACHINE.

1,387,182.

Specification of Letters Patent. Patented Aug. 9, 1921.

Application filed August 17, 1917. Serial No. 186,712.

To all whom it may concern:

Be it known that I, CHARLES E. RISER, citizen of the United States, residing at Dayton, in the county of Montgomery and State of Ohio, have invented certain new and useful Improvements in Contouring-Machines, of which the following is a specification.

My invention relates to wood working apparatus and more particularly to contouring or shaping means for wooden articles and especially adapted for contouring the heels of wooden shoe lasts. While the invention has been herein shown and described in its adaptation to the heel contouring operation upon shoe lasts, it is to be understood that it is not limited to this use or application, but is applicable to the contouring or shaping of other articles.

The object of the invention is to improve the structure, as well as the means and mode of operation of such apparatus whereby it will not only be cheapened in construction, but will be more efficient in use, positive in operation, accurate, economical, easily controlled, and unlikely to get out of repair.

A further object of the invention is to provide an improved form of cutter head having a draw cut action and to further provide improved forms of cutter blades having alternately arranged saw teeth for effecting the cutting action of the apparatus.

A further object of the invention is to provide improved means for controlling the cutting operation to produce a predetermined contour.

A further object of the invention is to provide improved means for regulating the contour controlling devices whereby the position of the contoured surface may be varied in its relation to the body of the article.

A further object of the invention is to provide an improved form of swinging carrier for the work or article operated upon.

With the above primary and other incidental objects in view as will more fully appear in the specification, the invention consists of the features of construction, the parts and combinations thereof, and the mode of operation, or their equivalents, as hereinafter described and set forth in the claims.

The preferred form of several forms of embodiment of my invention is illustrated in the accompanying drawings, in which

Figure 1 is a top plan view of the assembled machine or apparatus. Fig. 2 is a side elevation thereof. Fig. 3 is a detail side elevation of the templet adjusting means. Fig. 4 is a detail bottom plan view of the templet supporting means. Fig. 5 is a front elevation of the revoluble cutter head showing the relative position of the work during the contouring operation. Fig. 6 is a rear elevation of a revoluble cutter head. Fig. 7 is a side elevation of a shoe last upon which is indicated by dotted lines the contouring operation to be performed.

Like parts are indicated by similar characters of reference throughout the several views.

In the turning of wooden shoe lasts or other articles which may be produced in pattern lathes or by like mechanism, there is left at one or both ends of the article a neck or sprue projecting beyond the normal lines of the article by which it was engaged by the chuck or center of the lathe according to the end upon which said extension or neck exists, during the process of turning. Inasmuch as the lathe cannot reduce that portion of the article by which the work is held, the shaping of the terminals must be effected by other means. Heretofore, various methods of contouring or shaping the ends of such articles have been employed such as band sawing, wabble sawing, by use of abrasive wheels or tools and by manual operation. By such means, however, it has been difficult to control the operation to such degree that every piece will be identical in contour or shape.

The present apparatus is designed to semi-automatically reduce the terminal of the article to a predetermined contour by a combined sawing and cutting operation which will produce the desired outline without chipping, checking or otherwise mutilating the work.

In Fig. 7 there is shown the outline of a shoe last, the heel portion of which has been shown by solid lines as it leaves the chuck of the lathe. By dotted lines in said figure the contour of the finished heel of the last has been indicated. The purpose of the present apparatus is to remove the excessive material from the heel, reducing it to a predetermined outline or contour, as indicated by dotted lines in said Fig. 7.

Referring to the drawings, 1 is the main

frame of the machine or table upon which the operating portions of the apparatus are mounted. Secured to the top of the frame or table 1 are uprights or standards 2—2 in 5 which is mounted the main drive shaft which carries intermediate said standards 2—2 a drive pulley 3. The main drive shaft carries at its forward end a revoluble cutter head 4 the face of which as shown in Fig. 10 5 presents a surface having therein a plurality of tangentially arranged slots 6. In Fig. 5, there has been shown a series of four of said slots. It is to be understood, however, that the number of slots may be varied. 15 In practice, quite good results have been obtained by the use of three slots. The back of the cutter head 4 has been recessed or cut away to form a series of inclined bearing faces or surfaces 7 obliquely arranged in 20 relation with the flat face of the cutter head and intersecting said cutter head at the outer edges of the tangentially arranged slots 6. Adjustably mounted upon each of the inclined faces or surfaces 7 of the cutter head 25 is a cutter blade 8 the operative edge of which overhangs the outer edge of the slot 6 and is provided with a series of angular serrations or saw teeth 9. The saw teeth are formed in the cutter blade preferably at 30 an inclination to the plane of the blade whereby the transverse line of the tooth, that is the line of the point, will be substantially parallel with the axis of rotation of the head although it has been found in practice beneficial to give the cutting blade a slight clearance on the heel or rear of the last. That is to say, the transverse face of the cutting blade is not exactly parallel with the axis of oscillation but is inclined slightly 35 40 rearwardly and away from the center of oscillation whereby the forward side of the cutting blade will be thrust slightly deeper into the work.

Not only are the cutting blades 8 serrated or provided with saw teeth, but the teeth of succeeding blades are oppositely disposed, that is to say, the teeth of each succeeding blade 8 are arranged in reverse relation whereby the teeth of one blade are inclined 45 50 toward the right and the next blade toward the left. These cutting blades 8 are attached to the inclined faces 7 upon the rear side of the revoluble head 4 by means of clamp bolts 10 which engage in slots 11 in said cutter blades. By this means the cutter blades 55 may be adjusted upon the head independent of each other to a proper working position.

As the work is pressed against the face of the revoluble cutter head in the position 60 shown in Fig. 5, the cutting blades 8 are not only given a slicing or cutting action but they are also given a draw cut by which a sawing operation is afforded. This will be best illustrated by the series of dot and dash lines in Fig. 5 illustrating successive posi-

tions of the cutter blade in approaching and cutting through the work. By comparing a given point upon the work with the extremity of the cutting edge where it intersects the periphery of the head, it will be 70 seen that in each successive position a different point upon the cutting edge is brought into operative engagement with the work whereby a considerable length of the cutting edge is utilized. There is thus afforded 75 a peculiar combination of a chopping or slicing and a sawing operation which is found very effective in removing the small portion of material ordinarily necessary to be removed. The stem of the chuck neck 80 or spud is ordinarily so short that it cannot ordinarily by any means be removed in one piece but is disintegrated in its removal. The present device reduces this portion to sawdust without marring or tearing the body 85 of the article which has been a common fault of the method heretofore employed.

In order to support the work during the contouring operation there is provided a swinging carrier comprising upright rock 90 arms 12 carried upon a transverse rock shaft 13 mounted in suitable bearings 14 upon the main frame or table 1. Pivoted intermediate the upper or free ends of the rock arms 12 is an oscillating substantially U-shaped 95 yoke 15. In a medial position this yoke 15 carries a transverse work supporting platen 16 on which is adjustably mounted a guide or stop 17 against which the work, whether the same be a shoe last or other article is 100 abutted. The platen 16, preferably although not necessarily, is provided with a scale of graduations by which the stop or abutment 17 may be positioned. The yoke 15 and work platen forming a part thereof is 105 capable of a double swinging movement. The said yoke swings in its bearings in the upper ends of the rock arm 12 independent of the movement of the rock arm and is capable of a further movement about the axis of the 110 rock shaft 13 in unison with the swinging movement of the arms 12. By the latter of these movements, that is, the swinging of the rock arms 12, the work is moved to and from the revoluble cutter head 4 and by the 115 first of the mentioned swinging movements, that is, the swinging of the yoke in its bearings in the rock arms 12, the work is oscillated while in engagement with the revoluble cutter head in order that the cutting blade 120 may reach all portions of the heel contour.

The oscillatory yoke 15 is provided with an arm 18 carrying a counter balance weight 19 by which the swinging of the yoke is facilitated. The rock arms 12 are normally 125 oscillated toward the cutter head by means of a cable 20 attached to one of the rock arms and passing over a guide pulley 21, which cable carries at its lower end a suspended weight, not shown in the drawing. 130

In order to predetermine the contour of the terminal, whether same be the heel of the last, or the end of some other article, there is provided a templet 22 which operatively engages a stop member 23 and thereby not only predetermines the shape of the surface operated upon but also the length of the article by limiting the surface in its relation with the stop member 17. As shown in Fig. 3 the templet 22 is shaped to the desired contour. The templet 22 is pivoted as at 23 upon a vertically adjustable head 24 slidably mounted upon the yoke 15 and controlled by the adjusting screw 25. By adjusting the screw 25 the templet 22 may be raised or lowered in relation to the work upon the platen 16. In addition to this vertical adjustment the templet is capable of an oscillatory adjustment about its pivotal connection 23. This oscillatory movement is effected by means of a vertically movable slide 27 slidably mounted in the head 24 and longitudinally adjustable by means of the adjusting screw 28. Slide 27 carries a 25 stud or pin 29 engaging in a slotted opening 30 in the rear end of the templet 22, whereby the vertical adjustment of the slide 27 will effect an oscillatory movement of the templet about its pivot 23. This swinging adjustment varies the degree of the general direction of the heel surface to the general action of the last or causes the contour to recede to a greater or less degree. The vertical adjustment of the head 24 and with it the bodily adjustment of the templet, varies the height of the swell of the last heel. The stop member 23' is adjustable forwardly and rearwardly to vary the point of engagement of the templet by means of an adjusting screw 31.

In operation, the last or other article to be operated upon is placed upon the platen 16 with one end against the abutment 17. The controlling templet 22 having been previously adjusted, the work is swung toward the revolving cutter head by the oscillation of the rock arms 12 about the axis of the rock shaft 13. With the work pressed in engagement with the face of the revolving cutter head, the yoke 15 is oscillated in its bearings in the rock arms 12, thereby bringing all portions of the heel into operative engagement with the cutter blades. In this oscillatory movement of the yoke the templet 55 22 riding upon its stop will have a camming action to effect a slight oscillatory movement of the arms 12 which causes the work to approach to or recede from the revolving cutter head thereby determining the curvature 60 of the operative cut.

From the above description it will be apparent that there is thus provided a device of the character described, possessing the particular features of advantage before enumerated as desirable but which obviously is

susceptible of modification in its form, proportion, detail construction or arrangement of parts, without departing from the principle involved or sacrificing any of its advantages.

While in order to comply with the statutes, the invention has been described in language more or less specific as to certain structural features, it is to be understood that the invention is not limited to any specific details, but that the means and construction herein described comprise but one mode of putting the invention into effect, and the invention is therefore claimed broadly in any of its possible forms or modifications within the scope of the appended claims.

Having thus described my invention, I claim:—

1. A machine for shaping the ends of shoe lasts wherein the last is guided through an oscillatory movement in a plane perpendicular to the plane of rotation of a rotary cutter head by which the end of the last is reduced to predetermined contour, characterized by a series of cutter blades arranged on said head in angular relation one with the other to agree with the sides of a regular polygonal figure concentric with the center of rotation of the head, the radial distance of said blades from the center being substantially coincident with the point of application of the last to the head.

2. A machine for shaping the ends of shoe lasts wherein the last is guided through an oscillatory movement in a plane perpendicular to the plane of rotation of a rotary cutter head by which the end of the last is reduced to predetermined contour, characterized by a series of cutters carried by said head extending in directions tangential to a circle common to all the cutters and substantially intersecting the point of application of the last to the cutter head.

3. A machine for shaping the ends of shoe lasts wherein the last is guided through an oscillatory movement in a plane perpendicular to the plane of rotation, of a rotary cutter head by which the end of the last is reduced to predetermined contour, characterized by a series of cutters carried by the head and arranged in such relation as to successively form portions of the sides of a regular polygonal figure concentric with the center of rotation of the head.

4. A cutter head comprising a flat rotary face plate, and a series of cutting blades carried thereby, said blades being arranged tangentially to a common circle substantially tangent to the point of application of the work whereby said cutting blades form the successive sides of a polygonal figure, and means for supporting the work in proximity to the circumference of said circle.

5. A cutter head comprising a flat rotary face plate, and a series of cutting blades carried thereby substantially tangent to a common circle in such relation that the inner 5 end of each blade if projected would intersect the outer portion of the succeeding blade of the series, and means for presenting the work in close proximity to, but outside said circle.
- 10 6. A cutter head comprising a rotary member having a series of cutting blades carried thereby, said blades being arranged thereon substantially perpendicular to the radial position of the work at the time of 15 engagement therewith, and means for pre-

senting the work perpendicular to the plane of rotation of the head.

7. A cutter head comprising a rotary face plate and a series of cutting blades carried thereby, each blade extending toward the 20 periphery of the head at right angles to the radius of the head which intersects the right angle cutting blade adjacent to the inner end thereof.

In testimony whereof, I have hereunto set 25
my hand this 26th day of July A. D. 1917.

CHARLES EUGENE RISSE.
